UNITED STATES PATENT OFFICE.

FRANK U. WAGNER, OF MILFORD, INDIANA.

PICTURE-BOOK.

1,028,921.

Specification of Letters Patent. Patented June 11, 1912.

Application filed October 31, 1908. Serial No. 460,509.

To all whom it may concern:

Be it known that I, FRANK U. WAGNER, citizen of the United States, residing at Milford, in the county of Kosciusko and State 5 of Indiana, have invented certain new and useful Improvements in Picture-Books, of which the following is a specification.

This invention is a picture book and has for its object to provide a book having on 10 its leaves incomplete pictures or designs which are completed by a design on the cover of the book visible through the incomplete portions of the pictures on the leaves.

The blank or incomplete portions of the pictures are holes in the leaves, and the design 15 on the cover is in relief and is visible through the holes.

In the accompanying drawing, Figure 1 is a front view of the book. Fig. 2 is a perspective view showing the book open. Fig. 20 3 is a sectional view on the line 3—3 of Fig. 1.

Referring specifically to the drawing, 5 denotes the front cover; 6 the back cover; 25 and 7 the leaves of a book. On the inside of the back cover is a picture or a design 8. This is a human figure, the head 9 of which is in relief. Each leaf contains a picture or design 10 having a blank portion which is 30 made by cutting a hole 11 in the leaf. In the present instance the pictures are human figures in various poses, the holes 10 being in place of the heads of said figures. The holes are all in line with the relief 9 which is

visible therethrough thus completing the 35 pictures on the leaves.

When the book is opened at any of its leaves the relief will be brought into view through the holes 11 so that the pictures 10 will be displayed in complete form. If desired, the front cover can also be provided with a picture 12 and a hole adapted to co-operate with the relief 9 in the same manner as the pictures and holes of the leaves.

The invention can also be applied to tablets, calendars and various advertising devices and novelties.

The relief can be made of rubber, papier-mâché or other suitable material.

I claim:—

A book having designs on its leaves and on the inside of its rear cover, a portion of the cover design being formed in relief, and a portion of the design on each leaf being cut away to provide a sight opening, all of 55 said openings registering with each other and with the cover design to form a passage into which the relief portion of the cover design projects, to complete the design of any leaf at which the book is opened, and to 60 emphasize the completed portion of such design.

In testimony whereof, I affix my signature in presence of two witnesses.

FRANK U. WAGNER.
